UNITED STATES PATENT OFFICE.

WILLIAM WILSON, OF BLOOMINGTON, ILLINOIS.

STEAM-ENGINE.

SPECIFICATION forming part of Letters Patent No. 339,961, dated April 13, 1886.

Application filed December 19, 1885. Serial No. 186,229. (No model.)

To all whom it may concern:

Be it known that I, WILLIAM WILSON, residing at Bloomington, in the county of McLean and State of Illinois, and a citizen of the United States, have invented a new and useful Improvement in Steam-Engines, of which the following is a full description, reference being had to the accompanying drawings, in which—

- 10 Figure 1 is a section through the center of the steam-cylinder, but through the steam-chest, so as to cut through one of the ports in both of the valve-seats. Fig. 2 is a plan showing the steam-chest in place with its cover removed. Fig. 3 is a section through the cylinder on line xx of Fig. 4. Fig. 4 is a plan of the cylinder with the steam-chest removed, showing the steam-passages to, in, and from the cylinder. Fig. 5 is a cross-section through 15 the steam-chest at line w of Fig. 6. Fig. 6 is a side elevation of the steam-chest. Fig. 7 is a section through the steam-chest at line zz of Fig. 5, looking in the direction of the arrow, and showing the exhaust-valve seat. Fig. 8 20 is a section through the steam-chest on the line yy , looking in the direction of the arrow, and showing the admitting-valve seat. Fig. 9 is a plan view of the admitting valve and stem, looking at the face side of the valve. 25 Figs. 10 and 11 are, respectively, side and end views of the same. Fig. 12 is a plan of the exhaust valves and stem, looking at the face side of the valves; and Figs. 13 and 14 are, respectively, side and end views of the same. 30 The leading object of my invention is to provide a cylinder and steam-chest for a steam-engine, and especially for a locomotive, in which a valve is used for admitting and cutting-off purposes, and valves for release purposes, 35 all contained in one steam-chest, but in different compartments, each valve covering multiple ports, thereby securing a complete and constant release, which I accomplish as illustrated in the drawings, and hereinafter described.

In the drawings, M represents a steam-cylinder; N, a steam-chest.

The chest is partially divided into three longitudinal compartments by means of partitions $a b$, which are provided with ports, and serve the purpose of valve-seats. That portion of the steam-chest marked K is one of

the compartments, and extends the whole length of the chest. That portion marked L is another compartment, which also extends 55 the entire length of the chest. The central portion or compartment between the two valve-seats is divided into two parts or chambers, S T, by a partition, d, at the center, through which partition the exhaust-valve stem works 60 in a steam-tight sleeve.

O represents the admitting-valve, which controls the ports $t' t' v' v'$ in the valve-seat a . f is the valve-stem.

P R are the exhaust-valves.

e is that portion of the valve-stem g of the exhaust-valves which moves in the steam-tight sleeve in the partition d . It is unnecessary to show such sleeve, there being nothing peculiar about its construction. The exhaust-valves P R control, respectively, the exhaust-ports $p' p' r' r'$. These valves O, P, and R are designed to be operated by the valve-gear described in my Patent No. 333,706, dated January 5, 1886.

A is the steam-passage leading from the boiler to that portion of the chest lettered K.

B is a passage which leads from one of the chambers, T, between the two partitions or valve-seats $a b$ to one end of the steam-cylinder, and B' is another passage which leads from the other chamber, S, between the two valve-seats $a b$ to the opposite end of the steam-cylinder.

C C are exhaust-passages leading from the chamber L in the steam-chest to a common exhaust-passage, C'.

The operation is as follows: Steam passes from the boiler through the passage A into that portion of the steam-chest marked K, and at the proper time the admitting-valve O simultaneously opens the ports $v' v'$ and allows the steam to pass through them into the chamber T between the two valve-seats $a b$, from which chamber T steam passes into the passage B, (see Figs. 3 and 4,) and through such passage B to one end of the cylinder. The admitting-valve then closes the ports $v' v'$, and at the proper time the exhaust-valve opens the ports $r' r'$ and allows the steam to escape 100 through the chamber T and ports $r' r'$ into the compartment L and out through the passages C C' C'. Then the admitting-valve opens the ports $t' t'$, and allows steam to pass from the

compartment K into the chamber S, from which chamber it then passes through the passage B' to the opposite end of the cylinder, and then the admitting-valve closes the ports 5 t t' , and the exhaust-valve at the proper time opens the ports p p' , and the steam, having done its work, escapes through the chamber S and ports p p' into the compartment L, and is exhausted through the passages C C'.

10 The valves can be so made and adjusted that the admission-valve will admit and cut off steam, as desired, and so that the proper exhaust-valve will open at the proper time, and there will be a complete and constant release; and hence while the steam is working expansively it will not have to overcome the usual resistance on the opposite side of the piston. At the same time the desired steam-cushion can be provided for near the end of 15 the stroke.

What I claim as new, and desire to secure by Letters Patent, is—

1. The combination of the steam-chest provided with two partitions and valve-seats a b , each having ports, with a space between the 25 valve-seats divided into two parts or chambers by a partition, d , with an admission-valve and exhaust-valves, substantially as and for the purposes specified.

2. In combination with a steam-cylinder, a 30 steam-chest provided with partitions and valve-seats a b , each having ports, a chamber, K, to receive steam from a boiler, chambers T S between the two valve-seats, a chamber, L, to receive exhaust-steam, an admission-valve, exhaust-valves, a passage for the admission of steam from the boiler to the chamber K, passages from the chambers T S to the steam-cylinder, and exhaust-passages C C, substantially as and for the purposes specified.

WILLIAM WILSON.
